DESIGN FOR A MAGAZINE AND PAPER HOLDER

Richard Newman, New York, N. Y.

Application November 27, 1945, Serial No. 124,104

Term of patent 7 years

(Cl. D33—2)

To all whom it may concern:

Be it known that I, Richard Newman, a citizen of the United States, residing at New York, in the county of New York and State of New York, have invented a new, original, and ornamental Design for a Magazine and Paper Holder, of which the following is a specification, reference being had to the accompanying drawing, forming a part thereof.

In the drawing:

Fig. 1 is a perspective view of a magazine and paper holder, showing my new design;

Fig. 2 is a top plan view; and

Fig. 3 is a rear elevational view of the same.

I claim:

The ornamental design for a magazine and paper holder, as shown.

RICHARD NEWMAN.
